UNITED STATES PATENT OFFICE.

ADOLPH DELKESCAMP, OF WATERBURY, CONNECTICUT.

WAGON-WHEEL.

SPECIFICATION forming part of Letters Patent No. 268,635, dated December 5, 1882.

Application filed May 20, 1882. (No model.)

To all whom it may concern:

Be it known that I, ADOLPH DELKESCAMP, a citizen of the United States, and a resident of Waterbury, in the county of New Haven and 5 State of Connecticut, have invented a new and valuable Improvement in Wheels for Vehicles; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical sectional view of the wheel. Fig. 15 2 is a front view.

This invention has relation to wagon or carriage wheels to be manufactured of iron or steel; and it consists in the construction and novel arrangement of the axle-box having a 20 shoulder around its body portion facing toward its threaded end, an annular spoke-holder fitting on said axle-box, and having lateral rim-flanges inclined upward and perforated to receive the threaded ends of the oblique or staggered spokes, the interior and exterior nuts engaging said threaded ends and rim-flanges, and the main fastening-nut engaging the threaded end of the axle-box, all as hereinafter set forth.

In the accompanying drawings, the letter *a* 30 designates the axle-box, which is formed with the inner tapering bearing, *b*, for the spindle *c*, and is threaded exteriorly at *d* around its outer end. A shoulder, *e*, is made around its 35 body portion, facing its threaded end, and between said shoulder and threaded end is a round bearing, *g*. On this bearing fits the eye *h* of the spoke-holder *K*, which is of annular form, consisting of a body, *l*, and lateral annular flanges *f*, inclined upward and outward 40 from its outer or rim portion. These rim-flanges are on each side of the body portion of the spoke-holder, and when the latter is in place on the axle box there is on each side an annular recess, *m*, between the rim-flange and 45 the axle-box. The rim-flanges are somewhat outwardly inclined or flaring, the inclination of each flange being such that a plane tangent thereto at the point of engagement of one of the oblique or staggered spokes *N* is normal to 50 the axial line of the spoke. Each flange is provided with a series of perforations, *p*, and the perforations of the two series are arranged in zigzag order, to provide for the alternation of the spokes in their engagement with the threaded 55 perforations *r* of the rim or hoop *S* of the

wheel. These perforations are bored obliquely in two directions alternately to suit the inclined spokes of each side of the wheel. The spokes *N*, are simple rods or tubes having threaded ends *s* to engage the perforations *r* of the hoop *S*, and threaded ends *s'*, which pass through the perforations *p* of the rim-flanges of the spoke-holder. Before each spoke is passed through its perforation in the rim-flange it is provided with an outer or shoulder nut, *z*, which is designed to bear on the outer surface of the rim-flange. The end of the spoke which projects through the rim-flange within its cavity is provided with an inner or tie nut, *z'*, whereby the end of the spoke is securely connected to the rim-flange. By manipulating these nuts the hoop can be tightened or loosened at any point and its circular form rectified. Engaging the threaded end of the axle-box is the large main nut *V*, which secures the spoke-holder firmly in position against the shoulder *e* of the axle-box. The inner and outer nuts of the spokes bear firmly against the rim-flanges, because of their inclination or flare, and the joint at this portion is therefore very strong.

Ornamental caps *w* may be located at the ends of the spokes next the hoop and spoke-holder, if desired.

The entire wheel can be taken apart and put together with great facility. Its parts are exceedingly simple in form, and easily replaced if broken or injured.

Having described this invention, what I claim, and desire to secure by Letters Patent, is—

An iron or steel wheel having an axle-box formed with a shoulder, *e*, and threaded end *d*, the annular spoke-holder *K*, having the eye-bearing *h*, and the inclined or flaring rim-flanges *f*, perforated at *p*, the oblique or staggered spokes *N*, having threaded ends, and the outer or shoulder nuts, *z*, and inner or tie nuts, *z'*, engaging the rim-flanges and threaded ends of the spokes, and the large nut *V*, securing the spoke-holder to the axle-box, substantially as specified.

In testimony that I claim the above I have hereunto subscribed my name in the presence of two witnesses.

ADOLPH DELKESCAMP.
